CLAIM

The ornamental design for a location tracking device and clip, as shown and described.

DESCRIPTION

FIG. 1 is a front perspective view of a location tracking device and clip showing our new design.

FIG. 2 is a back perspective view of the location tracking device and clip.

FIG. 3 is a front view of the location tracking device and clip.

FIG. 4 is a rear view of the location tracking device and clip.

FIG. 5 is a side view of the first side of the location tracking device and clip.

FIG. 6 is a side view of the second side of the location tracking device and clip.

FIG. 7 is a top view of the location tracking device and clip; and,

FIG. 8 is a bottom view of the location tracking device and clip.

Throughout the Figures, aspects shown in broken lines are not considered a portion of the claimed ornamental design.
